Patented Nov. 14, 1961

191,747

LANGUAGE LABORATORY STUDENT BOOTH

Sydney W. Jentzen, Bloomfield Hills, Mich., assignor to
Jentzen-Miller Company, Troy, Mich., a corporation
of Michigan

Filed May 19, 1960, Ser. No. 60,650

Term of patent 14 years

(Cl. D33—11)

Fig. 1

Fig. 2

FIG. 1 is a perspective view taken to one side of a language laboratory student booth showing my design. FIG. 2 is a similar view taken to the other side thereof. The back of the booth is plain.

I claim:

The ornamental design for a language laboratory student booth, as shown and described.
